UNITED STATES PATENT OFFICE.

SAMUEL SCHRAGO, OF LOS ANGELES, CALIFORNIA.

PRESSURE-RELIEF ATTACHMENT FOR PENS.

Application filed August 9, 1926. Serial No. 128,129.

This invention relates to improvements in penholders and particularly to pen holders which have embodied thereon pressure relief devices so that the pressure will be properly applied by the hand to the penholder to enable the person using the holder to write with it very easily and in such a manner as to nicely shade the characters which he forms with the pen.

10 An object of this invention is to provide a pen holder having a pressure relief attachment which may be easily, quickly and cheaply constructed and which will not get out of order.

15 Another object of this invention is to provide an attachment providing a pressure relief device which can be easily and quickly attached to penholders of the conventional construction.

20 With the foregoing and other objects in view which will be made manifest in the following detailed description and specifically pointed out in the appended claims, reference is had to the accompanying drawings for an 25 illustrative embodiment of the invention, wherein:

Figure 1 is a side elevation of one form of the improved pen holder,

Fig. 2 is a vertical section taken substantially on the line 2—2 of Fig. 1,

Fig. 3 is a side elevation, parts being broken away and shown in section, illustrating a slightly modified form of construction,

Fig. 4 is a side elevation illustrating a further modified form of construction,

Fig. 5 is a vertical section taken substantially on the line 5—5 of Fig. 4, and

Fig. 6 is a side elevation, parts being broken away and shown in section, illustrating a further modified form of construction.

Referring to the accompanying drawings wherein similar reference characters designate similar parts throughout, and particularly to Fig. 1, the reference character 10 designates the body of the penholder, which is similar in construction to the conventional penholder having one large end and the other tapered. In the large end there is formed a bore 11, in which is a split tubular member 12 which serves to hold the pen point P in place. The large end of the penholder shown in Fig. 1 is split longitudinally, as indicated at 13, from the pen point end of the holder back to a point remote from this end, or to a point adjacent the center of gravity of the penholder. About the large end there is dis-

posed a metallic band 14 which has tongues or lugs 15 provided on it which are pressed into the body of the pen holder. The upper portion of the band is lengthened, as indicated at 16, to provide a finger rest and this portion is spaced slightly from the top surface of the penholder. By this construction the lower split half 17 of the penholder is somewhat yieldable, and in use when pressure is applied to the finger rest 16 by the forefinger, it will be transmitted from the finger rest back through the yieldable lower portion 17 of the penholder 10 to a point adjacent where the penholder rests on the crotch of the hand between the thumb and forefinger. This causes the pressure to be transmitted to the proper part of the penholder, so that in writing the nibs of the pen points will be split and allowed to contract very nicely to form a nice shading on the letters or characters written.

The modification shown in Fig. 3 accomplishes the same purpose as that shown in Figs. 1 and 2, but is of a different construction. In this modification the body of the penholder 18 is longitudinally split throughout a portion of its length, as indicated at 19, providing a yieldable lower half 20. A transverse cut 21 defines the forward end of the yieldable half which is disposed a short distance back from the pen point end of the holder. In the upper half of the body of the holder there is formed an aperture 22. A finger rest 23 which is disposed above the top of the large end of the body of the penholder has an angular shank 24, which extends through the aperture 21 and is fastened to the forward end of the lower yieldable half 20. This penholder operates in a similar manner to that shown in Fig. 1, that is, when pressure is applied to the finger rest 23, it will be transmitted therefrom through the shank 24 to the yieldable lower half 20 which in turn will transmit it to the body of the penholder at a point remote from the pen point end of the penholder.

In the modification shown in Fig. 4 there is provided an attachment which can be applied to the conventional penholder. In this modification there is a split spring ring 25 which on being thrust onto the body 26 of the penholder over its tapered end will be expanded thereby and thus the ring 25 will clamp on the body at a point remote from the penpoint or large end of the holder. A leaf spring 27 has one end secured to the under

side of this ring and extends forwardly therefrom, and has its forward end secured to the under side of a ring 28 which is somewhat greater in diameter than the diameter of the 5 large end of the penholder. The top of this ring is provided with the finger rest 29 spaced slightly from the top of the penholder. On applying pressure to the finger rest 29 the 10 pressure will be transmitted back to a point adjacent the center of the penholder as previously described in connection with the 15 modifications shown in Figs. 1 and 3.

Fig. 6 illustrates a further modified form of 20 construction for accomplishing the desired 15 result. In this modification a conventional penholder 30 has an aperture 31 formed vertically therethrough adjacent its large end. The finger rest 32 which is disposed adjacent the large end has an angular shank 33 extending through the aperture 31. The lower 25 end of this shank is bent backwardly providing a leaf spring 34, which is fastened as by a tack 35 against the under side of the body of the pen holder. The pressure applied to the 30 finger rest 32 will be transmitted through the shank 33 and the spring 34 to a point on the penholder well back from the pen point end of the holder.

From the above described construction it 35 will be appreciated that all of the modifications have finger rests on the body of the penholder slightly above the top surfaces and adjacent their large ends, and that a yieldable construction which may be separate or integral with the body of the penholder serves 40 to transmit pressure applied to the finger rest back to a point remote from the pen point and to a point on the under side of the holder. By this arrangement of parts it will be found 45 that the pen point can be caused to write very nicely and shade nicely, which is quite difficult if the penholder has the pressure applied directly to it from its top surface adjacent its pen point end.

50 It will be understood that various changes may be made in the detail of construction without departing from the spirit and scope of the invention as defined by the appended claims.

55 I claim:

1. A penholder having a yieldable part extending from a point remote from the pen point and toward the pen point end on the under side thereof, a finger rest arranged 60 upon the upper side of the body of the holder adjacent the pen point end and spaced slightly therefrom; and means connecting the finger rest to the forward end of said part.

2. In a penholder, a yieldable part extend-

65 ing from a point remote from the pen point and toward the pen point and on the under side thereof, a finger rest arranged upon the upper side of the body of the holder adjacent the pen point end and spaced slightly therefrom, and means extending through the penholder connecting the finger rest to the forward end of said yieldable part.

3. A pen holder comprising a body, a finger rest arranged upon one side of the body adjacent the pen point end, yieldable means arranged upon another side of the body and connected to the body more remote from the pen point end than the finger rest and extending toward the pen point end, and means connecting the finger rest to the forward end of 75 the yieldable means so as to normally keep the finger rest spaced from the body.

4. A pen holder comprising a body, a finger rest arranged above the top of the body adjacent the pen point end, yieldable means arranged upon the under side of the body, one end of which is secured to the body and means connecting the other end of the yieldable means to the finger rest so as to normally keep the finger rest spaced from the body.

5. A pen holder comprising a body, a finger rest arranged above and spaced from the top of the body adjacent the pen point end and means forming a yieldable connection between the finger rest and the under side of the body, part of said means extending transversely of the body adjacent the finger rest and the pen point end of the body.

6. A penholder comprising a body split longitudinally throughout a portion of its length to a point remote from the pen point end thereof, means for securing a pen point to that portion of the penholder above the split, a finger rest arranged and spaced above the upper portion of the holder adjacent the pen point end, and means connecting said finger rest to that end of the lower portion of the holder proximal to the pen point end.

7. A penholder comprising a body split longitudinally throughout a portion of its length to a point remote from the pen point end thereof, means for securing a pen point to that portion of the penholder above the split, a finger rest arranged and spaced above the upper portion of the holder adjacent the pen point end, the after portion of said finger rest being bent to extend transversely of the penholder and secured adjacent that end of the lower portion proximal to the pen point end.

In testimony whereof I have signed my name to this specification.

SAMUEL SCHRAGO..
